LOUIS ALFRED JENNY, OF DUMONT, NEW JERSEY.

RADIO TUNING DEVICE.

Application filed May 17, 1924. Serial No. 714,051.

My invention relates to improvements in radio tuning devices, an object of the invention being to provide an improved arrangement of tuning coils in which an outer primary coil has pivotally mounted therein upon the same axis a plurality of other coils. More specifically the invention includes an outer primary coil, enclosing a portion or all of a secondary and tertiary coil inside of the primary coil, which triplex arrangement is placed over a standard bulb and socket, thereby obtaining a very efficient coil and saving considerable space in the set. I attain these objects by arranging these coils, bulb and socket as illustrated in the accompanying drawing in which;

Figure 1 shows a view of the primary coil, consisting of a suitable tube, having two independent sets of windings consisting of a suitable number of turns of covered wire as indicated at 4 and 5.

Figure 2 is a top view of these coils, in which the secondary coil 6 is placed inside the primary coil and the tertiary coil 7 is placed inside of coil 6, held in place by screws 8 and sleeves 10.

Figures 3 shows the secondary coil 6 and the tertiary coil 7 placed inside of the primary coil. Both coils 6 and 7 are tilted to a fixed angle held by screw 9.

Each of these coils 6 and 7 consist of suitable tubing, having a suitable number of windings 11 and 12 of covered wire leading

to a tap screw, for connections, on the primary coil.

If used as a 4 circuit tuner each of the windings 4, 5, 11 and 12 is used separately. If used to tune 2 or 3 circuits any two sets of windings, such as 5 and 11, may be connected together.

In order to save some space and increase the efficiency of the tuner by obtaining the shortest possible connections from bulb to coil and to prevent loss of energy as much as possible, a socket 13 and a bulb 14 are placed inside of the tertiary coil as illustrated.

I am aware that prior to my invention radio tuning devices for two, three and four circuit apparatus have been made. I therefore do not claim such a combination broadly; but

I claim:

A radio tuning element of the character described comprising a primary coil, a secondary coil within and substantially concentric with the primary coil, a tertiary coil within and substantially concentric with the secondary coil, said coils being pivotally mounted with respect to one another on axes transverse to the axes of the coils, and a vacuum tube and socket disposed within a central space abounded by said coils, whereby electrical connectors between said coils and said tube may be of minimum length.

L. A. JENNY.
